ELECTRICAL RHEOSTAT ASSEMBLY

Edwin W. Drewitz and Victor Stein, Flushing, N. Y., assignors to De Jur-Amsco Corporation, Long Island City, N. Y., a corporation of New York

Application July 20, 1954, Serial No. 444,462

2 Claims. (Cl. 201—48)

This invention relates to electrical rheostats and potentiometers and relates more particularly to improvements pertaining to the manufacture of rheostat parts and their mode of assembly.

The prime object of our invention is to improve the production technique of precision rheostats and potentiometers. In accordance with the principles involved, the rheostat parts are designed to comprise a plurality of independent, pre-finished sub-assemblies which lend themselves to be assembled into a diversified series of rheostats and potentiometers by simple, rapid and semi-skilled production steps.

One of the principal sub-assembly components of the rheostat of the invention comprises the resistance element. This is designed so that it may be prepared in advance, apart from the other rheostat or potentiometer elements, inspected for electrical characteristics, and thus being finished in all respects may be stocked for subsequent inventory selection and use in the assembling of the complete rheostat. The structure of the resistance element sub-assembly is also such that it is rendered adaptable for a variety of changes in the distribution of resistance values for any given resistance winding, to meet varying needs of service, this being a factor in the making of a diversified group of rheostats and potentiometers with the means of the same basic resistance element component.

Another sub-assembly component of the rheostat is the rheostat casing or housing with the resistance terminals insulatably carried thereby, designed so that the resistance element component may be assembled thereto by a simple drop-fitting step. This casing or housing component may itself be prepared by assembling together by simple production techniques the necessary parts to form the pre-finished housing component, with insulated terminals ready for electrical connection to the resistance parts of the rheostat. The casing or housing sub-assembly component is also designed so that it may be adapted for diversified production use.

To the accomplishment of the foregoing object, and such other objects as may hereinafter appear, our invention is directed to the electrical rheostat assembly sought to be defined in the appended claims taken together with the following description and the accompanying drawings in which:

Fig. 1 is a view of a plurality of rheostats or potentiometers embodying the structure of the present invention, the rheostats being shown assembled in tandem relation, the left side rheostat being taken in cross-section along the line 1^a—1^a of Fig. 2, and the right side rheostat being taken in cross-section along the line 1^b—1^b of Fig. 2.

Fig. 2 is a view of the left side rheostat of Fig. 1 when viewed along the line 2—2 of Fig. 1.

Fig. 3 is an exploded view of the parts employed for producing the assembly of the prefabricated resistance element and the casing or housing of the rheostat embodying the principles of the present invention.

2

Fig. 4 is a perspective view of the prefabricated rheostat casing or housing carrying the resistance terminals.

Fig. 5 is a perspective view of the assembly of the prefabricated resistance element and the prefabricated casing or housing therefor.

Fig. 6 is a perspective view of a prefabricated resistance element with various modifications for which the same is adaptable.

Fig. 7 is a perspective view of an element employed in the making of the prefabricated resistance element.

Fig. 8 is a perspective view similar to Fig. 6 but showing a modification of the prefabricated resistance element; and

Fig. 9 is a perspective view of a contact plate employed in the production of the completed rheostat or potentiometer.

Referring now more in detail to the drawings, and having reference first to the form of the rheostat or potentiometer depicted in Figs. 1 to 5 of the drawings, the essence of the improvements embodied in the present invention comprises an assembly A, as depicted in Fig. 5, made up of a sub-assembly casing C carrying the resistance terminals, as depicted in Fig. 4, and a sub-assembly resistance element R, as shown at the right hand side of Fig. 3 of the drawings, these parts being shown in finally assembled relation in the completed rheostat or potentiometer in Figs. 1 and 2 of the drawings.

The sub-assembly resistance element R comprises one of the principal sub-assembly components of the rheostat, and consists of a prefabricated unit designed for being electrically tested and stocked for future selection and use in the assembling of the completed rheostat. This unit comprises an accurately ground insulator tube 10 functioning as a retainer for the resistance winding 12 united to the interior wall of the insulator tube 10. The winding 12 (made in the usual way by winding resistance wire around a flexible strip) which may be provided with the terminal bands 14 is fitted to the interior wall of the insulator tube 10 and is made to conform to the precision tube by cementing, heat and pressure, pressure being applied by an expanding arbor during the cement curing cycle. The result is the prefabricated unit R comprising the resistance winding mounted within and firmly united to the precision insulator tube 10. This unit is prepared, apart from the other potentiometer elements, is passed through the tests for determining its electrical characteristics and is stored or inventoried well in advance of its subsequent use in the assembly of any given rheostat.

This resistance unit or sub-assembly R, as thus constructed, is also rendered adaptable and lends itself for the making of a variety of changes in the distribution of the resistance values of the resistance winding, this being a factor, as heretofore indicated, in the making of diversified groups of rheostats or potentiometers by means of the same basic resistance element component. This latter is indicated in the modifications shown in Figs. 6 and 7 of the drawings. Referring first to Fig. 6 of the drawings the resistance unit or sub-assembly R' is there shown to comprise a precision insulator 10' and a resistance winding 12' united thereto, the insulator tube being provided with openings of predetermined area such as 16, 18 and 20 exposing the back of a selected number of turns of the winding, the said openings being filled with a conducting material such as 22 for "shorting out" the selected turns of the resistance winding. This may be readily accomplished in the unit R' by having the outer wall of the insulator tube 10' serve as an accurate mask for spraying low resistance materials in contact with the resistance winding to effectively "short out" any desired number of turns. This distribution of the resistance value for the resistance winding may be

obtained by insulating tubes having cutouts or openings of different areas, as is depicted by the insulating tube 12² shown in Fig. 7 having the openings 23 and 24.

The sub-assembly rheostat casing or housing C carrying the resistance terminals, shown as a sub-assembly in Fig. 4 of the drawings, and to which the resistance unit R is adapted to be mounted by a simple drop-fitting step is, itself, prepared by assembling together by simple production techniques the necessary parts separately shown in Fig. 3 of the drawings to form the prefabricated casing or housing component. Essentially the housing component comprises a metal, such as aluminum, tube 26, a number of resistance terminals 28, 28 and means generally designated as 30 for insulatably mounting the terminals on the metal tube 26. These parts also comprise connecting strips 32, 32 conductively attached to the terminals and adapted for solder connection to the resistance parts of the rheostat.

In Fig. 3 are depicted the parts and the mode of assembling the parts to form this casing or housing section C. The metal tube 26 formed at its ends with male and female grooves 34 and 36 for the purpose of coupling multiple sections (see Fig. 1), is provided with a plurality of orifices 38 for the reception of the terminals 28, 28, the terminals being insulated by means of the washers 40, 40 also received and fitted into the orifices 38. The means (30) for insulatably securing the terminals in position comprises preferably a first sheet or strip insulator 42 also orificed at 44, 44 (for registering with the orifices 38), and a second sheet or strip insulator 46 provided with irregular shaped openings, such as the square openings or orifices 48, 48, the insulator strip 42 being adapted to be fitted to the interior wall of the casing tube 26 and the insulator 46 being adapted to be fitted to the inside wall of the first insulator 42. These insulator strips are accurately dimensioned so that they may be assembled in the casing section C with their ends abutting as indicated for the insulator 46 at 50 (Fig. 4). For insulatably mounting the front of the terminals there is also provided an arcuately shaped insulator piece 52 provided with the registerable orifices 54, 54. The connecting strips 32, 32 are also provided with registerable orifices 56, 56. The terminals 28 are formed with irregularly shaped end such as the squared heads or portions 58 for fitting into the squared openings 48 in the insulator 46. For securing the terminals in position there may be provided the securing nuts 60, 60.

These described parts may be assembled to form the sub-assembly casing section C in a manner depicted by the sequential arrangement of the parts in Fig. 3 of the drawings. Connecting strips 32 are arranged between the insulators 42 and 46; these insulators are fitted into the housing tube 26 and the terminals are then threaded through the registering orifices, the terminals being locked against rotation by the interfitting of the terminal portions 58 in the squared openings 48, and the parts are locked in assembled position by the nuts 60, 60. The sub-assembly thus produced, as depicted in Fig. 4, is now ready for the drop assembly reception of the sub-assembly resistance component.

These sub-assemblies C and R may then be assembled by the simple forced insertion of the resistance component R into the casing component C to produce the unit shown in Fig. 5 of the drawings. The connecting strips 32, 32 may have their ends turned down as shown in Fig. 5 supported on an insulating ring 62. Selected ones of the connecting strips may then be connected by wire attachments 64 to selected sections of the resistance

winding, the end connecting strip 32 being in turn connected to a contact ring 66 as indicated for the left hand rheostat in Fig. 1 of the drawings.

In Fig. 8 of the drawings we show a modification of the resistance unit which permits of the elimination of the insulator strip 46. In this modification the resistance unit R³ comprises a precision retainer tube 10³ to which is united the resistance winding 12³ the insulator tube being formed with longitudinal grooves 68, 68. With this unit R³ the insulator strip 46 may be dispensed with, the longitudinal grooves 68, 68 being designed for the reception of the squared portions 58, 58 of the terminals, thereby locking the same against rotation, the connecting strips 32, 32 being also adapted to be received in for extension from these grooves.

A complete rheostat or potentiometer is made by interfitting an end wall 70 (see Fig. 9) to an end of the casing tube 26, the hub 72 of said end wall receiving a spacing collar 74 for mounting the rheostat shaft 76 to which is keyed an insulator plug 78 carrying a contact plate 80. The contact plate 80 shown in detail in Fig. 9 is provided with the balanced contact arms 82 and 84 provided with cylindrical elements 86, 88 for engaging the contact ring 66 (connected to the end terminal 28) the contact plate being also provided with brush contact elements 90 for riding over and engaging the resistance element 12. A plurality of these assembled units may be coupled together in tandem form by the interfitting of the male and female grooves 34 and 36. An end unit of a tandem assembly (or a separate rheostat or potentiometer) may be made by forming the end wall 92 (see the left hand unit in Fig. 1) integral with the casing tube 26. A group of rheostats arranged in tandem may be locked against endwise movement of the rheostat shaft 76 by means of locking rings 94, 94.

The improvements in the technique of producing precision rheostats and potentiometers of the present invention and the many advantages secured thereby will in the main be fully apparent from the above-detailed description thereof. It will be further apparent that many changes may be made therein without departing from the spirit of the invention defined in the following claims.

We claim:

1. A sub-assembly resistance element for drop-fitting into a casing to produce a rheostat assembly and defining a prefabricated resistance element designed for being electrically tested and stocked prior to making the rheostat assembly, comprising an accurately pre-dimensioned insulator tube and a resistance wiring unit united to the interior wall of the insulator tube, said insulator tube being provided with an opening of predetermined area to be filled with a conducting material for "shorting out" selected turns of the resistance winding.

2. The sub-assembly resistance elements of claim 1 in which the insulator tube is provided with openings of pre-determined locations and areas to be filled with a conducting material for "shorting out" selected turn sections of the resistance winding, the outer wall of said insulator tube serving as an accurate mask for spraying the conducting material into said openings.
